UNITED STATES PATENT OFFICE

2,498,545

LAPBOARD FOR IRONING MACHINES

Andrew H. Gerhardt, Skokie, Ill., assignor to Thor Corporation, a corporation of Illinois

Application August 24, 1945, Serial No. 612,356

2 Claims. (Cl. 38—68)

1

This invention relates to domestic types of ironing machines, and more particularly to a novel lap board construction and means for attaching the same to the machine proper. Lap boards for such machines usually serve as a rest or support for assisting the operator in manipulating articles preparatory to performing the ironing operation thereon, and also serve as a table or shelf for supporting ironed articles.

In the main, lap boards have heretofore been constructed in a manner so as to be permanently connected to the ironing machine and are usually formed and or mounted in a position and a manner which precludes efficient and convenient use.

One of the objects in the present invention is to provide a novel and improved lap board construction which may be quickly and easily detachably connected to the machine proper, and which is constructed and arranged to provide a shelf at one end of the machine for use in supporting ironed articles.

Another object is to provide a novel lap board construction wherein cooperating features are provided on the lap board and on the machine so as to quickly and easily detachably connect the lap board in operative position.

A further object is to provide an improved lap board construction comprising a pair of separate panel members adapted to be detachably mounted on the machine in a substantially, aligned horizontal plane and connected together to form supporting panels in front and at opposite ends of the machine.

A still further object is to provide an improved lap board construction and mounting means therefor which is simple in construction, durable, practical, and capable of being economically manufactured.

Other objects and advantages of this invention will be apparent from the following description, taken in connection with the accompanying drawing in which:

Figure 1 is top plan view of an ironing machine provided with the novel lap board construction embodying the present invention.

Figure 2 is a fragmentary, front elevational view of the machine with the lap boards in place, and with portions broken away to show details of construction.

Figure 3 is an enlarged view, part in section and part in elevation, taken substantially as indicated at line 3—3 in Figure 2.

Figure 4 is a view through the plane of juncture of the two lap board members, and taken sub-

stantially as indicated at line 4—4 on Figure 3.

Figure 5 is a fragmentary view of a portion of the front of the base of the ironing machine, showing the escutcheon plate for receiving cooperating elements of the lap board members.

The ironing machine as illustrated in the drawing includes an elongated base (10), having an upwardly extending support (11), adjacent one end, providing support for and enclosing driving connections to a rotatable, padded roll (12). Mounted on the base is an upwardly extending support arm to which is pivotally mounted a shoe element (14), adapted to be moved into and out of cooperative relation with the roll, in a well understood manner. It is to be understood that machines of the type illustrated in the drawing are usually mounted on a suitable stand or cabinet support, which has not been shown as it forms no part of the present invention.

10 The base of the ironing machine includes a main body (16), formed of sheet metal and the front central portion therefor is provided with an escutcheon plate (18), having an elongated, horizontally extending slot (19), as seen in Figure 5.

15 Said body (16), is closed at opposite ends by dome shaped members (22), which are preferably in the form of castings, and each of said end members is provided with an elongated, horizontally extending slot (24), disposed in substantially the same horizontal planes as the slot (19) of the escutcheon plate.

20 As shown in the drawing, the lap board construction embodying the present invention includes two angularly shaped members 25 and 26, of opposite formation, including main article supporting areas 25a and 26a and leg portions 25b and 26b respectively. When these members are connected to the base of the ironing machine, the main article supporting portions are disposed at opposite ends of said base, and the leg portions are disposed in front of the base, as clearly seen in Figure 1 of the drawings. Rigidly connected as by screws (30) to the underside of the inner edge of the article supporting area of each lap board member is a lug or projection (31), having an arcuately formed tongue (32). These projections are positioned so that the arcuately extending tongue is adapted to be inserted into and substantially occupy the cross sectional area of the slots (24), in the end members (22) of the base of the machine.

25 Mounted on the underside of and adjacent to the abutting ends of the leg portions of the lap board members are fittings (35) and (36) secured in place by screws (37). Said fittings are each

provided respectively with tongue projections (38) and (39) adapted to be projected into the slot (19) of the escutcheon plate (18) on the front of the base of the ironing machine. The fitting (36) is provided with a laterally projecting lug (40), adapted to be projected below an intermediate portion of the fitting (35), which is provided with a threaded thumb screw (42) adapted when the members are assembled as seen in the drawing, to be threaded firmly against a seat in the form of a slight recess, in the lug (40), as clearly seen in Figures 3 and 4 of the drawing, thus securing the two lap board members in connected relation to the base of the ironing machine.

In applying the lap board members to the base of the ironing machine, one of the members, and for example the member 25, is first positioned so that the tongue projection 32 of the lug 31 is projected into the adjacent slot 24 at the end of the base of the machine, in a direction as indicated by the arrow designated A. The lap board member is then rocked in a horizontal plane in a direction such as indicated by the arrow B until the tongue 38 of the fitting 35 is seated in the slot 19 of the escutcheon plate. The other lap board member 26 is similarly mounted in place and the abutting ends of the leg portions of the lap board members are firmly interconnected by the thumb screw 42 for securely retaining the lap board members in operative position, as above described.

It will be apparent that by virtue of the construction above described, the lap board members may be quickly and easily detachably connected to the base of the ironing machine. Furthermore, due to their size and shape said members may, when not in use, be conveniently stored in a suitable out-of-the-way place. As shown, the lap board members are in the form of metal castings, and may also be satisfactorily produced in molded plastics, or as sheet metal stampings. When the members are formed as castings, preferably light weight metal is employed, such as aluminum.

Although I have herein shown and described a certain preferred embodiment of my invention, manifestly it is capable of modification and rearrangement of parts without departing from the spirit and scope thereof. I do not, therefore, wish to be understood as limiting this invention to the precise embodiment herein disclosed, except as I may be limited by the appended claims.

I claim:

1. In combination, an ironing machine having an elongated base provided with a front wall and end walls, a lap board comprising two oppositely formed angularly shaped members each having a main article supporting portion and a connect-

ing leg portion, and adapted to be operatively associated with said base in opposed, substantially horizontal relation with the main portions of said members disposed in close relation to and constituting shelves at each end of said base, and with the leg portions positioned in close relation to the front wall of the base with the outer free ends of said leg portions disposed in substantially abutting relation, means comprising cooperating interengaging features on said end and front walls of the base and at correspondingly related locations on the respective portions of each of said members for detachably securing said members to said base, and means for detachably locking the outer ends of said leg portions of said members together for releasably securing said members in operative relation to the base.

2. In combination, an ironing machine having an elongated base provided with a front wall and end walls, a lap board comprising two oppositely formed angularly shaped members each having a main article supporting portion and a connecting leg portion, and adapted to be operatively associated with said base in opposed, substantially horizontal relation with the main portions of said members disposed in close relation to and constituting shelves at each end of said base, and with the leg portions positioned in close relation to the front wall of the base with the outer free ends of said leg portions disposed in substantially abutting relation, means comprising interengaging features on said end and front walls of the base and at correspondingly related locations on the respective portions of each of said members for detachably securing said members to said base, said means comprising horizontally disposed, elongated slots in said end and front walls of the base, and cooperating, laterally extending lugs on the respective portions of each of said members, and means for detachably locking the outer ends of said leg portions of said members together for releasably securing said members in operative relation to the base.

ANDREW H. GERHARDT.
